UNITED STATES PATENT OFFICE

FREDERICK L. G. STRAUBEL, OF GREEN BAY, WISCONSIN

FILING DEVICE

Application filed October 15, 1930. Serial No. 488,799.

My invention relates to filing drawers and more particularly it relates to panels or plates providing spacers forming partitions separating the contents of the drawer.

5 An object of the invention is the provision of a filing drawer having spaced apart vertical sides and a plurality of spacing plates located in the drawer and extending between the sides, and means for tilting the plates or 10 panels a predetermined amount to the vertical whereby said panels remain in parallel relation when in their inclined positions.

Another object of the invention is the provision in a panel or plate of the kind described of a novel reenforcing strip providing means for tilting the panel, and a mounting means for a stop member limiting the amount the panel or plate may be inclined to the vertical.

20 Still another object of the invention is the provision of panels or plates of the kind described having improved stop means operating to limit the inclination of the panels to the vertical a predetermined amount.

25 A further object of the invention is the provision of panels or plates of the kind described having improved reenforcing strips so constructed as to provide pivot arms about which the panels rotate.

30 Another object of the invention is the provision of a panel or plate of the kind described having reenforcing strips for its vertical edges, providing improved mounting means for stop members projecting therefrom.

35 A further object of the invention is the provision of a spacer panel or plate of the kind described which is simple, durable, reliable, efficient and satisfactory for its intended purpose.

40 Many other objects and advantages of the construction herein shown and described will be obvious to those skilled in the art from the disclosure herein given.

45 To this end my invention consists in the novel construction, arrangement and combination of parts herein shown and described and more particularly pointed out in the claims.

50 In the drawing wherein like reference

characters indicate like or corresponding parts,

Fig. 1 is a side elevational view of a filing drawer equipped with panels or plates embodying the devices of my invention;

Fig. 2 is a view along the line 2—2 of Fig. 1;

Fig. 3 is a view along the line 3—3 of Fig. 4;

Fig. 4 is a view along the line 4—4 of Fig. 3; and

Fig. 5 is a perspective view of a lug member forming a portion of the device.

Referring now more particularly to the drawing, the invention is embodied in a device comprising a drawer having sides 10, a bottom 12, and a tiltable end 14, and a plurality of guide panels 17 positioned in the drawer in predetermined spaced apart relation.

The end 14 is connected to the bottom 12 by hinges 15 and is tilted by means of a handle 16. The drawer is equipped with a follower (not shown) which is movable back and forth in the usual manner to provide a rear adjustment for the filing space. The contents of the drawer are carried by a plurality of card panels 20 and in the event the follower has only a back and forth movement for adjustment there is no compensation for various thicknesses of partly and completely filled card panels. The card panels 20 are unequally tilted and the capacity of the files is crowded at the bottom with the result that the V spread is greater at the top than is desirable. A plurality of guide panels 17 are positioned in the drawer to maintain a constant V-spread and prevent undue crowding of the contents in the bottom of the drawer. The guide panels 17 are spaced apart sufficiently to contain a plurality of card panels 20. A group of three to five of the card panels 20 may be positioned between the guide panels 17 with desirable results.

The guide panels 17 and the card panels 20 are all preferably provided with lugs 25 in the bottom of which wires 26 are hingedly mounted. The lugs 25 project downwardly into a channel 13 provided in the bottom 12 for that purpose and the panels are anchored

in the usual manner by a longitudinal rod 27 which is inserted between the wire 26 and the main body of the lug 25. The connection of the lugs 25 with the rod 27 permits the panels 17 and 20 to be tilted forwardly or rearwardly as shown in Fig. 1.

The panels 17 may be of any desired material such for example as cardboard, and the vertical edges are reinforced by U-shaped strips 18 which are clamped or closely fit the edges of the panel and project downwardly through apertures 19 arranged in rows adjacent the sides 10 of the drawer. The lower projecting end portions of the strips 18 also assist in anchoring the panel 17 against movement other than the forward or backward tilting thereof. The panels 17 project upwardly beyond the sides 10 a substantial amount. The folded portion of the strip 18 is provided with a slot 22 through which a tongue 24 forming a part of a stop member 23 projects. The plate 17 has a recess 21 adjacent the slot 22 and the main body of the stop member 23 is preferably of the same thickness as the panel 17 with the stop member of a size and shape to substantially fill the aperture or recess 21. The tongues 24 are so positioned as to permit the desired tilting of the panel 17 forwardly and backwardly and to provide stops which contact with the upper edge of the sides 10 to limit the inclination of the panels to the vertical a predetermined amount. The upper edges of the sides 10 are shown as turned outwardly to provide flanges 11 on which the tongues 24 rest. It is obvious that the panels 17 will thereby be held in parallel relation in their inclined position and that the V-shaped space will be maintained for all conditions of packing of the contents of the drawer.

The reenforcing strips 18 and the stop member 23 can both be cheaply manufactured by stamping or the like, and by making the thickness of the member 23 substantially identical with the thickness of the plate 17, the member 23 is quickly mounted in the reenforcing strips and the parts easily assembled.

Thus it will be seen that I have provided novel reenforcing means for panels or plates of the kind described and means for mounting the same in a drawer whereby the plates can be maintained in parallel relation when in inclined position and a predetermined V-shaped space of predetermined angle can be maintained without crowding the contents of the drawer at the bottom.

Having thus described my invention, it is obvious that various immaterial modifications may be made in the same without departing from the spirit of my invention; hence, I do not wish to be understood as limiting myself to the exact form, construction, arrangement and combination of parts

herein shown and described or uses mentioned.

What I claim as new and desire to secure by Letters Patent is:

1. A filing drawer having spaced apart vertical sides and a bottom having a row of apertures adjacent each side, a plurality of spacing plates located in the drawer extending between the sides, U-shaped reenforcing strips mounted on the vertical edges of each plate, said strips extending down into said apertures, the folded edge portions of said strips each having a slot and the plates each having a recess in each vertical edge adjacent a slot, and a member mounted in each of said recesses with a tongue portion projecting through the slot to engage the upper edge of the adjacent side to form a stop when the plate is inclined at an angle to the vertical. 70

2. A filing drawer having spaced apart vertical sides and a bottom having a row of apertures adjacent each side, a plurality of spacing plates located in the drawer extending between the sides, U-shaped reenforcing strips closely fitting the vertical edges of each plate, said strips extending down into said apertures, the folded edge portions of said strips each having a slot and the plates each having a recess in each vertical edge adjacent a slot, and a stop member having a body portion mounted in each of said recesses with a tongue portion projecting through a slot, said tongue portion being so positioned that it engages the upper edge of the adjacent side to form a stop when the plate is inclined at an angle to the vertical. 80

3. A filing drawer having spaced apart vertical sides and a bottom having a row of apertures adjacent each side, a plurality of spacing plates located in the drawer extending between the sides, mounting means for said plates preventing their removal from the drawer and permitting the plates to be tilted forwardly and rearwardly, U-shaped reenforcing strips mounted on the vertical edges of each plate, said strips extending down into said apertures, the folded edge portions of said strips each having a slot and the plates each having a recess in each vertical edge adjacent a slot, and a member mounted in each of said recesses with a tongue portion projecting through the slot to engage the upper edge of the adjacent side to form a stop limiting the tiltable movement of the plate forwardly and rearwardly. 100

In witness whereof, I hereunto subscribe my name this 6th day of October A. D., 1930.

FREDERICK L. G. STRAUBEL.
